CLIMBING TOY

Robert K. Hallum, Brownwood, Tex.

Application July 17, 1947, Serial No. 761,720

9 Claims. (Cl. 46—132)

1

This invention relates to new and useful improvements in toys.

The invention deals particularly with string actuated toys of the type wherein a figure or other object is caused to climb or descend a vertical length of string or cord, apparently without any effort or aid on the part of the user or operator of the toy.

One object of the invention is to provide a toy including a figurine suitably mounted upon a vertically stretched cord and adapted to descend the cord in a series of steps under the action and operation of the components of said figurine.

A particular object of the invention is to provide a toy, of the character described, which will descend a vertically stretched cord and which may be caused to ascend the cord through a slight manipulation of the cord by the operator or user of the toy.

Yet another object of the invention is to provide an improved toy wherein a figurine or other weighted object is resiliently mounted upon a vertically stretched string or cord so as to undergo oscillatory movement, and at the same time to ascend or descend the cord in accordance with the type of or lack of manipulation being carried out by the user of the toy.

An important object of the invention is to provide an improved toy having a suitable cord or other elongate flexible element upon which a suitable weighted figurine is flexibly and movably mounted with provision being made so that the operator of the toy may cause the figurine to move upwardly along the cord or downwardly therealong, the direction of movement and the change of direction of movement being affected at any time and at any point or place along the cord and entirely at the will of the operator.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a side elevation of a toy, constructed in accordance with the invention, and showing the several positions of the figurine in dotted lines,

Fig. 2 is an enlarged fragmentary view, in side elevation, of the mounting means for connecting the figurine to the cord,

Fig. 3 is a fragmentary side elevation, illus-

2

trating the operation of the toy when ascending the cord.

Fig. 4 is a fragmentary side elevation, illustrating the operation of the toy when descending the cord, and

Fig. 5 is an enlarged cross-sectional view taken immediately above the lower loop illustrating the movement of the supporting card within the loop.

In the drawing, the numeral 10 designates an elongate cord or string, or other suitable elongate, flexible member in the nature of a cord, such as a small, flexible, metallic cable, which may be usable in connection with the present invention. The cord 10 carries a loop 11 at its upper end, said loop being suitable for the reception of the finger or several fingers of the hand A of the operator of the toy. A similar, somewhat larger, loop 12 is provided at the lower extremity of the cord and is adapted to receive the toe or foot B of the user of the toy.

A suitable weight or figurine 13, which may be in the nature of a doll as shown in Fig. 1 of the drawing, or which may be a reproduction of any other desired object, such as a small animal or a geometrical figure, is adapted to be secured or connected to the cord 10. For the purposes of simplicity, the figurine 13 has been replaced in Figs. 2 through 4 by a ball or sphere 13'. However, it is to be kept in mind that any type of figure or object may be employed so long as it possesses the necessary mass or weight.

The figurine is secured to the outer end of an elongate, straight, spring rod or wire 14, the wire being of a resilient nature and formed preferably of a spring material such as high carbon steel. A ring or loop 15 is formed upon the inner end of the wire 14 and is preferably oval-shaped with its longer dimension in alignment with the longitudinal axis of the wire 14 so that the loop in effect forms a continuation of said wire. The plane of the loop 15 is at an angle with respect to the longitudinal axis of the wire 14 so that when said loop is in a horizontal plane, as shown in Fig. 2, the wire 14 projects laterally and slightly upwardly therefrom.

The loop 15 carries a vertically-extending connecting wire or bar 16 projecting thereabove, the upper end of the wire being formed into a ring helical coil 17 somewhat less in cross-sectional area than said loop. Of course, if desired, the coil 17, the wire 16, the loop 15, and the wire 14 may all be formed from one single piece of spring wire so as to simplify and reduce the cost of the manufacture of the device. Such is the preferred form of the invention, but it is to be

kept in mind that this mounting structure may be fabricated from a number of separate elements or pieces of wire secured or fastened together by suitable means, such as welding or brazing, or in some other suitable fashion.

The cord 10 extends through the coil 17 and also through the loop 15, it being pointed out that the wire from which this mounting structure is formed is preferably of somewhat smaller diameter than the cord 10 so as to be capable of engaging the cord with a considerable degree of friction. Obviously, if the wire from which the mounting structure is formed is too large in diameter, or if the cord 10 is quite inflexible in nature, the desired frictional engagement will not be obtained and the operation of the toy, to be described hereinafter, will be considerably impaired.

In the operation of the toy, the cord 10 is stretched in a taut manner between the foot B and the hand A of the user or operator of the toy. The figurine 13 may be assumed to be positioned somewhere near the central portion of the cord being connected thereto by means of the coil 17 and the loop 15 of the wire 14, the outer end of which carries said figurine. Due to the considerable mass of the figurine and the resilient or spring-like nature of the wire 14, as well as the length of the latter, the figurine may be caused to commence vibratory movement in a vertical plane by suitable lifting or depression of the figurine to deflect and bend the spring wire 14, which, upon release, in attempting to return to its straightened position, will start the figurine swinging in a vertical arc in the manner of a pendulum. Even without the influence of forces tending to continue this vibratory movement, the figurine will continue to oscillate in a vertical arc for a considerable period because of its mass and the spring nature of the wire 14, as described hereinbefore.

As shown in Fig. 2, the oval or elongate shape of the loop 15 will allow the cord 10, in effect, to move from one end of said loop to the other as illustrated by the full and dotted line positions of said cord. It is this relative movement of the cord back and forth within the loop 15 which causes the toy to either ascend or descend the cord 10. Also, the coil and loop and their connecting wire or bar may be formed of a single element having a tapered bore or passage. In effect, such a passage is formed by the coil, loop and bar.

In Fig. 3 is illustrated the operation of the toy in ascending the cord, the figurine 13 being replaced by the ball or sphere 13' for the purposes of simplicity. The full line illustration of the toy in this view shows the position of the ball 13' as it nears the center of its downward swing. At this point, the cord 10 is substantially in the center of the loop 15 so that the ends of said loop are not frictionally engaging the cord. However, due to the considerable mass of the ball 13' with respect to the mass of the relatively light wire 14 and loop and coil structures 15 and 17, there is very little tendency for the loop to move downwardly with respect to the cord during such downward movement of said ball. The ball passes fairly quickly to its lowermost position wherein the left-hand end of the loop, as viewed in Fig. 3, frictionally engages the cord and prevents movement of the loop with respect thereto. This frictional engagement also holds, in cooperation with the upper coil 17, the inner end of the wire 14 and halts the downward

swing of the ball 13. Being placed under a bending stress, the wire 14 causes the ball to commence its swing upward to its uppermost position as shown in dotted lines.

To cause the toy to ascend the cord, the operator allows said cord to slack a bit as the ball 13', or the figure 13, reaches its lowermost point of swing. As soon as the ball starts to swing upwardly, the cord is suddenly tightened by the operator so as to snap the wire 16 to an upright position and give added impetus to the ball 13' in its upward travel or swing. Being under the influence of this added momentum or impetus, the ball moves upwardly rather quickly and with considerable force. In the course of its upward travel and as it reaches the position again represented by the full line illustration in Fig. 3, wherein the cord 10 is free to pass through the loop 15, the ball, because of its considerably larger mass, causes the loop to move upwardly along the cord to the dotted line position shown. As the ball continues its upward swing and forces the right-hand end of the loop into engagement with the cord, the upward movement of the loop is halted and shortly thereafter the resilient force exerted by the wire 14 stops the upward swing of the ball. The dotted lines shown in Fig. 3 illustrate this position of the toy. The ball 13 then begins to drop both under the force of gravity and the force exerted by the wire 14 and again passes to its lowermost position from which the operator may cause the toy to rise a further distance along the cord by an alternate slackening and tightening of the cord. Thus, the operator of the toy may cause the figurine to apparently climb the cord 10 by a slight loosening or reducing of the tension placed upon the cord 10 as the figurine reaches the lowermost point of its swing and by suddenly tightening or increasing the tension placed upon the cord 10 as the figurine commences its upward swing.

To permit the figurine to descend the cord, the operator merely holds said cord under a reasonable degree of tension and allows the figurine to oscillate or vibrate upon the wire 14. This operation is illustrated in Fig. 4, the solid line illustrations showing the position of the toy upon the cord as the ball 13', representing the figurine 13, approaches or leaves the central portion of its swing. In this position, the cord is within the central portion of the loop and is not binding upon either end thereof. During the downward swing of the ball 13', there will be relatively little movement of the loop with respect to the cord for the reasons set forth hereinbefore. However, the ball, in swinging upwardly, travels a little slower due to the fact that it is overcoming the force of gravity through the resilient nature of the wire 14. In this slightly slower, upward travel, the ball, through its reluctance to move upwardly exerts a downwardly-directed force via the wire 14 upon the loop 15. Thus, as the ball nears its central position in its upward swing, the loop will be moved downwardly along the cord during the period of time before the ball completes its upward swing and causes the right-hand side of the loop to frictionally engage and bind upon this cord, as shown in dotted lines in Fig. 2. Having reached its upper position, the ball is stopped by the flexing of the wire 14 and caused to reverse its direction of movement and begins its downward swing. In the downward swing, the ball displays very little tendency to cause the loop 15 to move downwardly since the force of gravity is aiding the ball in such

downward movement. Conversely, the force of gravity impedes the upward movement of the ball so that such movement must be effected substantially solely by means of the wire 14, whereby a considerably greater tendency to cause the inner or looped end of the wire to move opposite the ball is displayed.

The operator of the toy may at will cause it to move downwardly along the cord by merely holding the cord in a taut position, or he may cause the toy to climb or ascend the cord by alternate slackening and tightening of the latter.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A toy including, an elongate flexible element in the nature of a cord adapted to be held taut in a substantially vertical position, a member having a vertical passage receiving the flexible element, said passage being larger at the lower end than the upper end, an elongate spring extending laterally from the member, and a weight secured to the outer end of the spring, whereby the member is caused to ascend or descend on the flexible element upon manipulations of said element.

2. A toy including, an elongate flexible element in the nature of a cord adapted to be held taut in a substantially vertical position, a member having a vertical passage receiving the flexible element, said passage being larger at the lower end than the upper end and being oval in outline at the lower end, an elongate spring extending laterally from the member, and a weight secured to the outer end of the spring, whereby the member is caused to ascend or descend on the flexible element upon manipulations of said element.

3. A toy including, an elongate flexible element in the nature of a cord adapted to be held taut in a substantially vertical position, a member having a vertical passage receiving the flexible element, said passage being larger at the lower end than the upper end and being oval in outline at the lower end, an elongate spring extending laterally from the member, and a figurine secured to the outer end of the spring, whereby the member is caused to ascend or descend on the flexible element upon manipulations of said element.

4. A toy including, an elongate cord-like element adapted to be held taut in a substantially vertical position, a bar disposed in substantially parallel relation with the element, a ring at the upper end of the bar encircling the element, a ring at the lower end of the bar encircling the element, the lower ring being larger than the upper ring, an elongate spring extending laterally from the bar and ring structure, and a weight secured to the outer end of the spring, whereby the bar and its rings are caused to ascend or descend on the cord-like element upon manipulations of said element.

5. A toy including, an elongate cord-like element adapted to be held taut in a substantially vertical position, a bar disposed in substantially parallel relation with the element, a ring at the upper end of the bar encircling the element, a loop at the lower end of the bar encircling the element, said loop being oval in shape and larger than the ring, an elongate spring extending laterally from the bar and loop structure, and a weight secured to the outer end of the spring, whereby the bar and loop structure is caused to ascend or descend on said cord-like element upon manipulations of said element.

6. A toy including, an elongate cord-like element adapted to be held taut in a substantially vertical position, a bar disposed in substantially parallel relation with the element, a ring at the upper end of the bar encircling the element, a loop at the lower end of the bar encircling the element, said loop being larger than the ring, an elongate spring extending laterally and slightly upwardly from the bar and loop structure, and a weight secured to the outer end of the spring, whereby the bar and loop structure is caused to ascend or descend on said cord-like element upon manipulations of said element.

7. A toy including, an elongate cord-like element adapted to be held taut in a substantially vertical position, a wire disposed in substantially parallel relation with the element, the upper end of the wire being formed into a coil encircling the element, the lower end of the wire being formed into a loop encircling the element, an elongate spring extending laterally from the loop, and a weight secured to the outer end of the spring, whereby the coil is caused to ascend or descend on the cord-like element upon manipulations of said element.

8. A toy including, an elongate cord-like element adapted to be held taut in a substantially vertical position, a wire disposed in substantially parallel relation with the element, the upper end of the wire being formed into a coil encircling the element, the lower end of the wire being formed into an oval loop encircling the element, an elongate spring extending laterally and slightly upwardly from the loop, the longitudinal axis of the spring being approximately parallel to the longer dimension of the oval loop, the spring, the loop, the wire and the coil being formed from one piece of spring wire, and a figurine secured to the outer end of the spring, whereby the coil is caused to ascend or descend on the cord-like element upon manipulations of said element.

55 9. A toy as set forth in claim 4 wherein the bar is substantially shorter than the spring.
